UNITED STATES PATENT OFFICE.

CHARLES VICTOR BOUILLON, OF PARIS, FRANCE.

CENTRIFUGAL MACHINE.

Application filed July 14, 1928, Serial No. 292,630, and in France June 6, 1928.

- Centrifuge apparatuses are known to the art which are employed for the separation of solid materials in suspension in liquids and having the form of a cylinder fitted 5 on its periphery with a series of juxtaposed receptacles of pyramidal or conical form, at the apexes of which the dirty liquid is evacuated through calibrated orifices in a continuous manner due to centrifugal force, 10 while the clarified liquid is evacuated, likewise in a continuous manner, in the vicinity of the apex of the apparatus.
- Such apparatuses, however, present disadvantages resulting chiefly from the rather 15 high speeds of rotation given to the apparatus. As a matter of fact, due to these speeds of rotation, the evacuation orifices placed at the apexes of pyramidal receptacles must be of very small dimensions, very 20 frequently less than 1 mm. in diameter, in such wise as to limit on the one hand the volume which said orifices give out, and on the other hand, the energy absorbed by the evacuation of said liquids whose velocity is 25 very high. Obviously the use of orifices of such small section necessarily causes obstruction thereof.
- The object of my invention reside in overcoming these disadvantages by means of an 30 arrangement in which the apexes of the pyramidal or conical receptacles are provided with evacuation channels in the form of small diverging cylindrical or conical blast nozzles whose axes are disposed sub- 35 stantially in the direction of centrifugal force, which channels are provided with a mechanical cleaning device consisting preferably of a blade or analogous expedient to which is given a movement of rotation and 40 which passes at each revolution over the evacuation orifice. Said blade is adapted to receive movement of rotation from a radially disposed rod into which it is fitted and is adapted to turn with light friction in a 45 conduit provided at the base of the centrifugal bowl. Said rod in turn receives a movement of rotation either from an independent motor or from the shaft of the decanting apparatus by means of any suitable speed reducing device. The thickness 50 of the blade being suitably chosen and the speed of rotation thereof being suitably regulated by means of properly designed gear ratios, the evacuation orifices, piercing 55 a plug and eccentrically disposed with respect to the axis of the blade, will thus be periodically cleaned. The shutter blade is preferably fitted to slide in the radial rod so that it is thrust by centrifugal force against the plug in which is pierced the 60 evacuation orifice.
- In the accompanying drawing I have represented, by way of example, one form of construction of the apparatus conforming to my invention. 65
- In the drawing—
- Fig. 1 is an axial section through a vertical type of decanting apparatus;
- Fig. 2 is a horizontal section on the line A—A of Fig. 1; 70
- Fig. 3 is a fragmentary sectional detail of the sediment evacuating apparatus; and
- Fig. 4 is a sectional detail on the line B—B of Fig. 3.
- Adverting to Fig. 1, the apparatus comprises a main frame casting 1 supporting and guiding the group of movable parts fixed to a central vertical arbor 2 resting on a lower step bearing 3 and guided by a middle support 4. Said arbor is preferably 75 driven by a belt passing over a pulley 6 but the said arbor might obviously be driven directly by an electric motor coupled directly thereto or other suitable means.
- The bowl of the decanting apparatus 7 is 80 fixed to the central arbor 2 and has a form of a truncated cone the larger base of which is constituted by a circular horizontal wall 8. The tapered part of the bowl is formed of two parts assembled by a joint 9 for introducing a series of truncated conical polarizing discs 10 destined to facilitate decantation in a manner well known in the art. 85
- The upper part of the central arbor 2 above the foot of the bowl is hollow and 90 serves for introducing the liquid to be treated, which liquid is lead in through the upper extremity 12 of the central arbor from whence it is distributed through perforations 13 provided in said arbor between the 95 polarizing discs 10.
- The bowl of the decanting apparatus consists, in a manner well known in the art, of a series of pyramidal forms 16 (Fig. 2) which are equally spaced and form empty 100 spaces of identical form between as shown at 17 which are also of pyramidal form and whose apexes 18 are situated on the largest diameter of the bowl.
- The solid particles are evacuated in the 105 pyramidal chambers 17 as hereinbefore indicated. For regulating the rate of evacuation

of sediment and preventing closing of the outlet orifices provided at the apex of each of the pyramidal chambers, I have provided a device represented conventionally in Fig. 5 1 and more in detail in Figs. 3 and 4.

Said device comprises a circular rod 34 adapted to turn with light friction in a horizontal radially disposed conduit 35 provided on the bottom of bowl 8. The conduit 10 begins at a slight distance from each of the apexes 18 of the pyramidal chambers 17. As shown in Fig. 1, the rod 34 receives movement of rotation from the main arbor 2. For this purpose, at its extremity situated at the center of the apparatus, the rod 15 34 traverses a support 36 and terminates in a bevelled pinion 37 which imparts a movement of rotation thereto from a bevelled gear. Said bevelled gear is integral with a socket 39 loosely mounted on the arbor 2 upon which it is supported through the medium of a ball race 40 bearing on a flange 41.

The socket 39 is likewise integral with a 25 toothed wheel 42 which is set in motion by a corresponding toothed wheel 43 keyed to an auxiliary arbor 44 parallel to the main arbor 2. Said auxiliary arbor carries at its lower end a gear 45 which receives movement from a toothed wheel 46 keyed on the main arbor. The auxiliary arbor 44 and the toothed wheels 43 and 45 are preferably supported by the main frame 1.

By suitably determining the ratios of 35 gears 42, 43, 45 and 46 forming a gear train any fixed speed that may be desired may be given to the bevelled gear 38 so that the angular speed of the six rods 34 may be adjusted as desired.

40 Each rod 34, at its extremity situated at the periphery of the cone, terminates in a device illustrated on a larger scale in Figs. 3 and 4. The circular rod 34 carries at its extremity an interior recess of square or 45 rectangular section, into which slides with light friction a square rod 47 provided at its extremity with a blade 48 of rectangular section. The outer face of said blade is adapted to bear on the inner surface 49 of a plug 50 screwed into the periphery of the bowl 55 and whose axis coincides with that of the rod 34.

For the purpose of easily replacing the inner face 49 of plug 50 subject to rubbing 55 by blade 48 in case of wearing thereof, I preferably provide a removable member therein in the form of a bar 51 fitted to the plug by means of a screw 52.

In order to assure exact centering exactly 60 the blade 48, said blade carries on its outer face a circular orifice 53 in which engages a pin 54 integral with the plug or movable piece 51 and is disposed along the axis of the plug.

65 At a suitable distance from its axis said

plug is provided with an eccentrically disposed orifice 55 through which peripheral evacuation of the dirty liquid takes place.

This orifice or channel is preferably given the form of a small blast pipe whose axis 70 is disposed in the direction of centrifugal force either of cylindrical form of small diameter as represented in Fig. 3 or in the form of a diverging cone.

The device above described operates in the 75 following manner:

When the particles of solid matter have once been separated and the liquid clarified they accumulate at the apex 18 of pyramidal chambers 17 in the form of sediment 80 and are solicited by centrifugal force and flow through the orifices 55 and 56 traversing the plugs 50. These orifices are sufficiently small that in spite of the high velocity of flow of the dirty liquid, the output 85 does not attain exaggerated values.

The sediment thus projected to the exterior is collected by the fixed peripheral collector 57 formed in the frame from whence a circular trough 58 receives them 90 (Fig. 1).

At the same time the six rods 34 are given a rotary movement about their axes, which movement is imparted thereto by the central shaft 2 by means of the train of reducing gears 42, 43, 45, 46 which gives them a movement of rotation sufficiently retarded through the medium of the toothed bevelled wheel 38 meshing with each of the pinions 37 keyed to the extremity of each 100 rod 34.

Under the influence of the movement of rotation of each of the rods 34, each blade 48 on the extremity is given a movement of rotation being driven by the square portion 105 47 thereof and guided by the centering pin 54 engaging the orifice 53. Since each blade is free to slide in its square recess 46 in the direction of its axis, the centrifugal force exerted on each blade presses it against the inner face 49 of plug 50 and at each revolution of said blade it passes over the orifice of channel 55 for cleaning and preventing its obstruction.

The movement of rotation of rods 34 about their axis may be obtained by other means if desired either being derived from the main arbor of the decanting apparatus or from an independent motor.

While I have described what I deem to be the preferable form of my device I do not wish to be limited thereto since there might be changes made in the construction and arrangement of parts without departing from the spirit of my invention as comprehended within the scope of the appended claims.

Having described my invention what I claim as new and desire to secure by Letters Patent is—

1. The combination of a decanting apparatus of the continuous rotary type having a plurality of tapered juxtaposed chambers and an orifice formed in the apex of each of said chambers for evacuating dirty liquid, a revolvable blade for each of said orifices eccentrically mounted with respect thereto, each of said blades being adapted to bear against the inner end of its respective orifice through the action of centrifugal force when revolved and means for rotating each of said blades to wipe its respective orifice during revolving thereof for cleaning and preventing obstruction of said orifices by sediment.
2. The combination of a decanting apparatus of the continuous rotary type having a plurality of tapered juxtaposed chambers, an orifice formed in the apex of each of said chambers for evacuating dirty liquid and a main driving arbor, a revolvable blade for each of said orifices adapted to be actuated by said main arbor, said blades being eccentrically mounted with respect to their respective orifices and adapted to bear against the inner end of their respective orifices through the action of centrifugal force when revolved and means independent of said main driving arbor for rotating each of said blades to wipe its respective orifice during revolving thereof for cleaning and preventing obstruction of said orifices by sediment.
3. The combination of a decanting apparatus of the continuous rotary type having a plurality of tapered juxtaposed chambers, an orifice formed in the apex of each of said chambers for evacuating dirty liquid and a main driving arbor, a radially disposed rod in each of said chambers, a blade feathered to each of said rods adapted to pass over the orifice corresponding thereto for cleaning and preventing obstruction of said orifices by sediment, a bevelled actuating pinion for each of said rods, a bevelled gear common to said pinions and a train of reduction gears interconnecting said common bevelled gear and said main driving arbor.
4. The combination of a decanting apparatus of the continuous rotary type having a plurality of tapered juxtaposed chambers, an orifice formed in the apex of each of said chambers for evacuating dirty liquid and a main driving arbor, a radially disposed rod in each of said chambers, a blade feathered to each of said rods adapted to pass over the orifice corresponding thereto for cleaning and preventing obstruction of said orifices by sediment, a bevelled actuating pinion for each of said rods, a bevelled gear common to said pinions and a train of reduction gears interconnecting said common bevelled gear and said main driving arbor.

In testimony whereof I have affixed my signature.

CHARLES VICTOR BOUILLON.
